ELECTROMAGNETIC RECOIL SYSTEM FOR
A GUN

George R. Carlson, Glencoe, Ahmed D. Kafadar, Chicago, and Severin Raynor, Winnetka, Ill., assignors, by mesne assignments, to the United States of America as represented by the Secretary of the Army

Application April 22, 1953, Serial No. 350,402

10 Claims. (Cl. 89—42)

The invention relates generally to recoil mechanisms for guns. More particularly the invention relates to improvements in recoil mechanisms of the type wherein electrical energy is utilized to produce the braking force.

Several factors must be considered when the effectiveness of a recoil mechanism is studied. Ambient temperature for example may prevent the usual hydropneumatic system from operating. The system is expected to function in substantially the same manner under any combination of climatic and terrain conditions which may be found on this earth, whether it is an arctic blizzard at -70° F., a tropical beach with salt spray and 100 percent relative humidity, or a desert with temperatures to $+150^{\circ}$ F. and blowing sand. In addition to the wide range of ambient temperature over which the mechanism must perform its own temperature is raised as a result of the energy it absorbs. Under conditions of rapid fire it is possible to attain a temperature of 300° F. or higher, so that the mechanism is actually expected to give satisfactory performance over a range of 400° F. Another limiting factor is the vulnerability of the standard hydropneumatic systems to enemy small arms fire and small shell fragments, because a slight dent in the cylinder wall is sufficient to cause the very rapid failure of a packing which must ride over it.

It is therefore a prime object of our invention to provide a novel recoil mechanism that is completely effective under all operating conditions and is easy and cheap to manufacture.

It is a further object of our invention to provide a gun recoil mechanism that will smoothly dampen the energy of recoil without damage to the gun and without change in operating characteristics under conditions of rapid fire.

It is a more specific object of our invention to dampen the linear motion of a gun barrel using the principle of the eddy current brake.

In the accompanying drawings in which a preferred embodiment is illustrated.

Figure 1 is a longitudinal section view of apparatus incorporating our invention.

Figure 2 is a cross section taken on line 2—2 of Figure 1 and looking in the direction of the arrows.

Figure 3 is a cross section taken on line 3—3 of Figure 1 and looking in the direction of the arrows.

Referring now more particularly to Figure 1 wherein a recoil means that functions as an eddy current brake is shown, and wherein similar reference characters indicate corresponding parts, numeral 1 indicates a gun barrel of conventional design adapted to move rearwardly upon discharge of the round. A spring 2 embraces the forward end of barrel 1 and urges between housing 3 and annulus 4 which is internally threaded to cooperate with mating threads cut into the barrel substantially as shown. An end plate 5 is secured by bolts 6 to a turned out flange on shroud 7 and carries annular rawhide buffer 8 for a purpose that will presently appear.

The eddy current brake comprises a core 13 surround-

2

ing and secured to barrel 1 by nuts 14 disposed at opposite ends thereof and carrying annular coils 15 and 16 electrically connected in series. Leads 9 and 10 for connecting the coils to a source of electrical energy are run through a hollow rod 22 which is constrained to move with the core as will later more fully be explained. A cylinder 17 of a metal of good electrical conductivity such as copper or aluminum surrounds core 13 and extends between end plates 5 and 18. Three tie rods, 21, 22 and 23 are secured to core 13 at their respective proximal ends and extend rearwardly therefrom. The tie rods pierce endplate 18 with a sliding fit and are secured at their several distal ends to movable plate 24 by nuts 25. Three tie rods 27, 28 and 29 are respectively threaded

15 at their proximal ends into armature 20 and extend rearwardly through endplate 18 and are secured by nuts 26 to movable plate 24 whereby the core and armature are constrained to move together, with the barrel, on opposite sides of cylinder 17, in recoil and countercoil motion.

20 The external surface of the recoil mechanism is formed by shroud 7 bolted or otherwise secured to plates 5 and 18 and carrying gussets 19 which bear trunnions 30 for supporting the weight of the gun.

In operation an electrical firing circuit is provided (not shown) which contains a relay which will not permit the gun to fire unless sufficient current is flowing in the coil windings. When the gun is fired the barrel moves violently backward, carrying with it the core and armature which, as explained above, are tied together by the 30 several tie rods and plate 24 and stores mechanical energy in the spring. As the core and armature move rearwardly the lines of flux, which are shown in dotted lines in the drawing, are continuously cut by the relative motion between the core and the cylinder. Eddy currents are 35 set up in the cylinder which produce flux which interacts with the main flux in the usual well known manner to give rise to a force which opposes the motion, and the barrel assembly is braked. When most of the recoil energy has been dissipated by the eddy current brake and 40 the remainder stored in the spring the barrel assembly comes to rest.

The stored energy in the spring is now used to return the gun to battery. As the assembly moves forward the 45 brake again comes into action and the core finally comes to rest against the front buffer.

The rifling torque tending to rotate the barrel is taken by the three tie rods 21, 22 and 23 and transmitted to the trunnions through plate 18.

50 We have found it convenient in practice to cause the core to act as a piston in a cylinder whereby air is drawn into the forward portion of the recoil assembly during recoil, said air being partly entrapped by a one way valve and allowed to escape slowly whereby the counter recoil motion is slowed.

55 The above described recoil structure was adapted for use with a 37 mm. cannon and the following values were recorded during testing of the piece:

60	Round No.	Charge, percent	Length of Recoil (Inches)	Current (Amperes)
1		50	4 $\frac{1}{4}$	51
2		75	4 $\frac{1}{4}$	51
3		75	4 $\frac{1}{4}$	51
4		100	5 $\frac{1}{4}$ 6	51
5		110	6	51
6		100	5 $\frac{1}{4}$ 6	51
7		100	6 $\frac{1}{4}$ 6	46

70 It will be seen from the above that the recoil means provided according to the present invention adequately absorbs the energy of recoil and counter-recoil in accord-

ance with the objects set forth. It will be understood, of course, that the form of the invention illustrated and described herein is a preferred embodiment and that numerous modifications and alterations may be made therein without departing from the spirit and scope of the invention as defined in the appended claims.

We claim:

1. A recoil mechanism for a gun comprising a support, a gun barrel reciprocatable in recoil and counterrecoil, a member of good electrical conductivity fixed to said support, electromagnetic flux generating means mounted adjacent said member and movable in unison with said barrel, and means for energizing said electromagnetic flux generating means whereby relative motion between the said electromagnetic flux generating means and said member during recoil and counterrecoil produce a force to oppose said motion.

2. A recoil mechanism for a gun comprising a support, a gun barrel reciprocatable in recoil and counterrecoil, a member of good electrical conductivity fixed to said support, electromagnetic flux producing means mounted for motion in unison with said gun barrel proximate to said member, and means for energizing said electromagnetic flux producing means whereby relative motion between the said electromagnetic flux producing means and said member generates a force to oppose said motion.

3. A recoil mechanism for a gun comprising a support, a gun barrel reciprocatable in recoil and counterrecoil, a member of good electrical conductivity fixed to said support, flux generating means mounted adjacent said member and movable in unison with said barrel whereby substantially all of the said flux passes through the said member, and means for energizing said electromagnetic flux generating means whereby relative motion between said flux generating means and said member during recoil and counterrecoil produces a force to oppose said motion.

4. A recoil mechanism for a gun comprising a support, a gun barrel movable relative to said support in recoil and counterrecoil, a member having a length at least equal to the movement of the said gun barrel in recoil and of good electrical conductivity fixed to said support, flux generating means mounted adjacent said member and movable in unison with said barrel whereby substantially all of the said flux passes through the said member, and means for energizing said flux generating means whereby relative motion between said flux generating means and said member during recoil and counterrecoil produces a force to oppose said motion.

5. A recoil mechanism for a gun comprising a support, a gun barrel movable relative to said support in recoil and counterrecoil, a member of good electrical conductivity and of a length at least equal to the movement of the said gun barrel in recoil fixed to said support, a magnetic circuit including a coil mounted adjacent said member and movable in unison with said barrel, and means for energizing said coil whereby the flux generated thereby passes through the said member and relative motion between said coil and said member during recoil and counterrecoil produces a force to oppose said motion.

6. A recoil mechanism for a gun comprising a support, a gun barrel movable relative to said support in recoil and counterrecoil, a cylinder of a metal of good electrical conductivity and of a length at least equal to the movement of said gun barrel in recoil fixed to said support in concentric relation to said barrel, a magnetic circuit including a coil mounted adjacent said cylinder and movable in unison with said barrel, and means for energizing said coil whereby the flux generated thereby passes through said magnetic circuit and a portion of said cylinder and relative motion between said coil and cylinder during

recoil and counterrecoil produces a force to oppose said motion.

7. A recoil mechanism for a gun comprising a support, a gun barrel movable relative to said support in recoil and counterrecoil, a cylinder of a metal of good electrical conductivity and of a length at least equal to the movement of said gun barrel in recoil fixed to said support in concentric relation to said barrel, a magnetic circuit concentric with said barrel and including an annular coil mounted adjacent said cylinder and movable in unison with said barrel, and means for energizing said coil whereby the flux generated thereby passes through said magnetic circuit and a portion at least of said cylinder and relative motion between said coil and said magnetic circuit during recoil and counterrecoil produces a force to oppose said motion.

8. A recoil mechanism for a gun comprising a support, a gun barrel movable relative to said support in recoil and counterrecoil, a cylinder of a metal of good electrical conductivity and of a length at least equal to the movement of said gun barrel in recoil fixed to said support and surrounding said barrel, a magnetic circuit in part at least between said barrel and said cylinder and movable in unison with said barrel, a coil in said magnetic circuit, and means energizing said coil whereby the flux generated thereby passes through said magnetic circuit and a portion at least of said cylinder and relative motion between said magnetic circuit and said cylinder during recoil and counterrecoil produces a force to oppose said motion.

9. A recoil mechanism for a gun comprising a support, a gun barrel movable relative to said support in recoil and counterrecoil, a cylinder of a metal of good electrical conductivity and of a length at least equal to the movement of said gun barrel in recoil fixed to said support concentric with said barrel, a magnetic circuit movable with said barrel and comprising a core embracing said barrel, a coil in said core and a yoke surrounding said cylinder, and means for energizing said coil whereby the flux generated thereby passes through the said cylinder and relative motion between said magnetic circuit and said cylinder during recoil and counterrecoil produces a force to oppose said motion.

10. A recoil mechanism for a gun comprising a support, a gun barrel reciprocable in recoil and counterrecoil, a member of good electrical conductivity having a length at least equal to the movement of said barrel in recoil affixed to said support, a core affixed to and encompassing said barrel, a plurality of annular coils provided within said core adjacent said member, means for energizing said coils to produce magnetic flux thereabout, a plurality of tie rods affixed to said core and extending rearwardly thereof coaxial with said barrel, an armature concentric with said barrel and spaced from said core by said member, a plurality of additional tie rods affixed to said armature and extending rearwardly thereof coaxial with said barrel, and a movable plate affixed to said plurality of tie rods and to said plurality of additional tie rods, said core and armature adapted to move with said barrel in recoil and counterrecoil relative to said member to induce eddy currents within said member to provide additional magnetic flux about said eddy currents, the eddy current flux adapted to interact with said coil flux to produce a force to oppose the motion of said core and said barrel.
